CLAIM

The ornamental design for a curved slide compact, as shown and described.

DESCRIPTION

FIG. 1 is a perspective view of a curved slide compact; FIG. 2 is a front elevation view of the curved slide compact of FIG. 1;

FIG. 3 is a top plan view of the curved slide compact of FIG. 1;

FIG. 4 is a back elevation view of the curved slide compact of FIG. 1;

FIG. 5 is a bottom plan view of the curved slide compact of FIG. 1; and,

FIG. 6 is a right-side elevation view of the curved slide compact of FIG. 1, the left-side elevation view being a mirror image of the right-side elevation view.

The broken lines form no part of the claimed design. The claimed design extends to the broken line boundary in FIG. 5, but does not include the boundary or the area within the boundary.
